BACK FOR A STADIUM SEAT

Wilmer R. Schultz, 1540 Chestnut St.,
Emmets, Pa. 18049

Filed Apr. 1, 1974, Ser. No. 456,633

Term of patent 14 years

Int. Cl. D6—00

U.S. Cl. D6—197

FIG. 1

6

FIG. 2

FIG. 3

FIG. 4

FIG. 5

FIG. 6

FIG. 1 is a perspective view of a back for a stadium seat, shown in my new design;

FIG. 2 is a front view of the back for a stadium seat illustrated in FIG. 1;

FIG. 3 is a top plan view of the back for a stadium seat;

FIG. 4 is a cross-sectional view taken along line 4—4 of FIG. 2 and indicating the appearance of the back for a stadium seat when considered in conjunction with FIG. 2;

FIG. 5 is a side view of the back for a stadium seat; and

FIG. 6 is a cross-sectional view taken along line 6—6 of FIG. 2.

I claim:

The ornamental design for a back for a stadium seat, as shown and described.
